DESIGN FOR A SHOE SKATE CLOG

James V. Lewis, Kansas City, Mo.

Application June 13, 1938, Serial No. 77,805

Term of patent 3½ years

To all whom it may concern:

Be it known that I, James V. Lewis, a citizen of the United States, residing at Kansas City, Jackson County, Missouri, have invented a new, original, and ornamental Design for a Shoe Skate Clog, of which the following is a specification, reference being had to the accompanying drawing, forming a part thereof.

In the drawing:

Figure 1 is a perspective view of a shoe skate clog, showing my new design.

Figure 2 is an inverted plan of the shoe skate clog.

Figure 3 is a central vertical longitudinal section of the shoe skate clog.

I claim:

The ornamental design for a shoe skate clog, as shown.

J. V. LEWIS.
